TOGGLE SWITCH

Christopher I. Smith, New York, N. Y., assignor
to Marks Products Co., Inc., Brooklyn, N. Y.,
a corporation of New York

Application February 16, 1935, Serial No. 6,774

8 Claims. (Cl. 200—67)

This invention relates to electrical switches and more particularly to wall switches for use in the wiring of rooms in buildings for light, power and portable electric devices.

5 It is a particular object of the present invention to provide a switch of compact design and special construction for use in connection with wall plates and gang boxes.

It is another object of the invention to provide a switch of this type having end terminals in order to permit the switch to be mounted in an outlet box, and a plurality of such switches to be conveniently mounted side by side in a single box as well as in a multiple gang box.

15 It is a further object of this invention to provide a fully enclosed switch having an insulating body of only two parts joined to each other.

With these and other objects in view the invention provides a switch which is extremely simple 20 in construction, easy to manufacture at a very reasonable price and which facilitates its assembly into gangs with other wiring devices.

The invention will be better understood from the description to follow taken in connection with 25 the accompanying drawings in which—

Figure 1 is a front elevation of a snap switch embodying the invention showing the switch attached to a bridge plate adapted for mounting in an outlet box.

30 Figure 2 is a side elevation of Figure 1.

Figure 3 is a sectional elevation on line 3—3 of Fig. 1.

Figure 4 is a sectional plan of the switch casing without the switch lever on line 4—4 of Fig. 3.

35 Figure 5 is a sectional elevation on line 5—5 of Fig. 1.

Figure 6 is a perspective detail of a right hand contact plate.

40 Figure 7 is a front elevation of a distance member.

Figure 8 is a sectional elevation on line 8—8 of Fig. 5.

Figure 9 is a top plan of the switch cover.

45 Figure 10 is a bottom plan of the switch cover.

Figure 11 is a sectional elevation of the switch lever on line 11—11 of Fig. 12.

Figure 12 is a side elevation of a switch lever assembly.

50 Figure 13 is a perspective view of a left hand contact plate.

Figure 14 is a side elevation of the switch cover.

Figure 15 is an enlarged perspective view of the switch casing, with part of the walls being 55 broken away for the sake of clearness.

Figure 16 is an enlarged perspective view of the switch casing with the walls intact.

Figure 17 is a view similar to Figure 16 but taken at right angles to the view of Fig. 16.

Referring to Figure 4 of the drawings, 15 represents a hollow switch casing preferably made of a single piece of phenolic compound and substantially rectangular in plan as well as in longitudinal and transverse elevations. The rear of casing 15 is completely closed and the front is open. 10 The longitudinal vertical side walls 151 and 153 of the casing are solid and integral with rear wall 155 and transverse end walls 152 and 154, and each of these has a rectangular aperture adjacent to bottom wall 155. In wall 152, this 15 aperture is close to side 151 and in wall 154 it is close to side 153. All of the walls are thin and the interior faces of end walls 152 and 154 are reinforced in their middle portions by heavy rectangular vertical ribs 156 which extend from the 20 rear wall 155 forward to about the middle of the casing. Two tapered posts 157 of thin but long rectangular cross section extend inward from rear wall 155 to near the middle of casing 15, parallel to and spaced a short distance from walls 20 151 and 153. Between posts 157 and each adjacent side wall a small rectangular rib 158 is provided by thickening rear wall 155. At each of the four interior corners of the casing 15 a vertical slot 159 is provided parallel to walls 151 and 30 153 at end walls 152 and 154, which extends downward from the top of casing 15 to near the aforescribed rectangular openings in these walls but not extending into these openings. The front of casing 15 is closed by cover 16 which is 35 also preferably made from a single piece of phenolic compound. It fits into recesses provided in walls 151 and 153. The inner faces of flanges 162 of cover 16 lean against the outer faces, and vertical ends 161 against the end faces of these 40 recesses. The flange portions 162 of cover 16 which fits into the recessed portion of casing 15 is square in plan, and two opposite corners are provided with rectangular cuts so that the small faces 163 engage the inner face of side walls 151 45 and 153 and prevent lateral motion of the cover when lodged upon the casing. On the square part 162 an octagon portion 164 is formed on the cover and the front portion 169 is rectangular in plan. The long sides of the rectangle extend in longitudinal direction of the casing when assembled thereon and the short sides transversely thereof. A rectangular aperture 165 is provided in this part of the cover for accommodation of the switch lever handle 191. The rear 50 55

side of cover 16 is hollow and provided with a deep but narrow transverse recess 166 for accommodation of pivot pin 193 which extends between the two longitudinal side walls 167. Two parallel deep narrow slots 168 extend along the middle portions of these walls.

In this housing the following switch apparatus is assembled:

Two metallic contact support members 17r and 17L, each consisting of a metallic strap which is bent angularly to provide a long leg 171 and a short terminal leg 172 perpendicular thereto, the latter being provided with a terminal screw 176. Each part 171 is provided at its lower narrow edge with a notch 173. These notches are equally spaced from terminal leg 172 in both 17r and 17L. The flat inner faces of 17r as well as of 17L have a contact spring 174 riveted thereto which extends on 17r from notch 173 towards the free end of 171 and on 17L in opposite direction towards terminal 172. On the upper narrow edges shallow longitudinal notches 175 are provided near 172. These contact supports are inserted into casing 15 through the rectangular openings in walls 152 and 154, during which operation they are tilted over posts 157 and finally contact support 17r rests along the inside of wall 151 and 17L along the inside of wall 153 on the rear wall 155 guided by posts 157 and either by side walls 151 or 153. In that position the notches 173 engage ribs 158 which prevent horizontal withdrawal of the contact blades when in their places. In vertical direction, the two contact blades 17r and 17L are each held in place by a distance member 18 of sheet insulating material which is slipped downward into a pair of slots 159 adjacent to the same side wall. Projection 181 of each distance member 18 engages notch 175 of the top edge of a contact blade 17 and corner 182 of distance member 18 is suitably cut that the lower edge of 181 may rest on the contact blade within notch 175. The upper horizontal edge of distance member 18 is provided with a projection 183 which has a semi-cylindrical journal notch 184 in its top face so positioned on distance member 18 that when assembled it lies in the transverse axis of the switch mechanism. The two distance members 18 are inserted in opposite directions in a pair of slots 159 of casing 15 above contact blades 17 to be pressed down on them by cover 16.

The switch lever 191 shown in Figs. 11 and 12 consists of a handle 191 preferably of phenolic insulating material having one of its end portions formed into a relatively large hub 192 through which passes a plain cylindrical pin 193 preferably of steel that protrudes equal distances from opposite faces of hub 192. Opposite the handle 191 a recess 195 is cut into the periphery of hub 192. Upon pin 193 is mounted a U-shaped bridge member 194 bent from sheet metal to form two parallel legs which are provided near their extremities with aligned apertures through which pivot pin 193 passes and then accommodate hub 192 between said legs. The bridge portion of 194 which joins the two legs to each other is provided with a tubular shaped aperture 198 through which passes the narrow portion of operator blade 196 which is surrounded by a helical spring 197. The wider upper part of blade 196 forms shoulders with the narrow portion which lean against the upper end of spring 197 and the extreme upper end of blade 196 leans against one corner of the recess 195 formed in hub 192. This switch lever 191 is inserted into the casing 15

when contact supports 17 and distance men 18 are assembled therein as heretofore described so that pivot pin 193 rests on the two semicircular journal notches 184 and bridge mem 194 in the hollow central part of the casing between posts 156 in longitudinal and posts 157 in transverse directions. (See Figs. 3, 4 and 5.)

Cover 16 is slipped over switch handle 191 which passes through rectangular aperture 165 therein while transverse recess 166 in the inner face of the cap slips over pivot pin 193. The two longitudinal recesses 168 slip over projections 183 of distance members 18 and corner notches 163 fit into the corresponding corners of the casing walls 151 and 153.

The cap 16 is fastened to casing 15 by means of a metallic bridge plate 21 adapted to be held on the front opening of a wall outlet box 22 by means of screws 212. The rectangular front portion 169 of the switch cover 16 fits closely into a corresponding aperture 201 in the center of wall plate 20 so that the front plane of this plate becomes flush with the face on 169. The middle portion 164 of cover 16 which is preferably octagonal in shape but may be keyed in this plate in any other suitable manner fits into a corresponding aperture in bridge plate 21. The wall plate 20 is fastened to bridge plate 21 by screws 202. Bridge plate 21 is provided with two longitudinal downwardly directed integral ribs 211 which extend along the outside of the side walls 151 and 153 of casing 15 and along the square portion 162 of cover 16. These ribs form means to reinforce bridge plate 21 and to align it with cover 16 and casing 15 during the assembling operation. When the complete switch is assembled with bridge plate 21, it is permanently fastened thereto preferably by two drive screws 212 which are driven through apertures in the bridge plate 21 into corresponding apertures in lugs 150 of the casing 15.

In the completely assembled switch perfect split journals are provided for switch lever pin 193, one half of each journal being formed by the semi-cylindrical notch 184 in distance member 18 and the other half of the journal by the semi-cylindrical bottom of each transverse recess 166 in cap 16. Longitudinal motion of pin 193 is prevented by side walls 167 of the cap against which the end faces of the pin fit closely. The two legs of bridge member 194 are guided between hub 192 and the longitudinal side walls of aperture 165 of the cover. When switch handle 191 is moved from the "off" position shown in Figures 1 to 3, operator blade 196 is moved downward and its narrow portion shifted through the aperture 198 in the bridge of 194 while the shoulders on 196 compress the spring 197. When this compression is so far advanced that the distance from the flat recess face 195 to the bridge of 194 is equal to the length of the blade between these elements, the upper end of blade 196 moves over to the opposite end of recess 195 and the expanding spring presses the bridge member over to form an angle with the axis of handle 191 on the opposite side thereof. This movement forces the legs of the bridge member 194 between contact springs 174 of 17r and 17L thereby closing the circuit between the terminal screws 176 in terminal 172 of contact supports 17r and 17L. The forming of any arc which might be caused in opening or closing the circuit between contacts 174 and bridge member 194 is prevented by the posts 157 which act as arc barriers between 75

these elements and by ribs 156 which act as arc barriers between the contact springs 174.

The special combination of elements in their relative positions produces an extremely small and compact toggle switch of the box type which not only may be mounted on a bridge plate for assembly on a wall plate but which permits the mounting of a plurality of such switches directly on a wall plate thereby eliminating the use of a bridge plate.

Changes in details may be made without departing from the principle of my invention and I desire to be limited only by the state of the prior art and the appended claims.

15 I claim:

1. In a switch, in combination, a casing of insulating material having an open front, a rear wall, integral side and end walls, each end wall having a perforation for a contact support member adjacent to said rear wall at diagonally opposite corners, a pair of contact support members each extending from one of said perforations along one of said side walls, projections on said rear wall holding said support members against 25 longitudinal and lateral motions, a groove formed at the interior ends of each side wall extending from said support to the open front of said casing, a distance member guided in each pair of grooves, a journal groove on each distance member and a cover on said casing having an aperture and a pair of transverse recesses therein, a switch handle passing through the aperture of said cover and a pivot pin for said handle journaled between the bottom walls of said recesses and the top of said distance member within 35 the grooves therein.

2. In a switch adapted for attachment to a wall plate or a bridge member having an opening, in combination, a box like casing of insulating material having an open front and consisting of a rear wall, side walls and end walls integral with each other, recesses formed in the front edges of two parallel walls, a square-shaped cover closing the front of said casing having a base portion 40 fitting into the recesses on said casing, notched corners interlocked with the casing walls, a middle portion of polygonal shape above said base portion adapted to fit the opening in said bridge member and a rectangular front portion adapted 45 to fit the opening in the wall plate and having an aperture therein, and switching mechanism in the casing including an operating lever extending outwardly through the aperture.

3. A switch casing of insulating material consisting of a rear wall, side walls and end walls, all of said walls being integral with each other, a cover perforated for the reception of a switch handle, a switch mechanism within said casing operable by said handle and positioned between 50 said side walls, a contact support member at the inside of each side wall having a terminal thereon passing through a perforation in one of said end walls and a recess in its bottom face and a lug on said rear wall adjacent each side wall engaging the recess in said contact member to lock it against longitudinal motion.

4. A switch casing of insulating material consisting of a rear wall, side walls and end walls, all of said walls being integral with each other, a 55 cover perforated for the reception of a switch handle, a switch mechanism within said casing operable by said handle and positioned between said side walls, a contact support member at the inside of each side wall having a terminal there-

on passing through a perforation in one of said end walls and a recess in its top face, slots formed in said end walls parallel to and adjacent said side walls, a plate slidably mounted in a pair of said slots, a projection on the bottom of said plate 60 engaging the recess in the top face of said contact member, the top face of said plate being engaged by said cover forming means to secure said contact member and plate in fixed position within in said casing.

5. In a switch, in combination, a casing consisting of bottom, side and end walls, a hollow cover for said casing, contact support members held in recesses in said end walls at two diagonally opposite corners of the casing and having ends 10 lodged in slots formed at the other two diagonally opposite corners of the casing, a distant member slidably mounted in the slots of said casing between the top of said contact member and said cover to hold said contact member in place, 15 switching mechanism mounted in said casing having a handle extending through an aperture in said cover and a pivot pin for said handle mounted between said distance member and said cover.

6. A switch casing of insulating material consisting of a rear wall, side walls and end walls, all of said walls being integral with each other, a cover perforated for the reception of a switch handle, a switch mechanism within said casing operable by said handle and positioned between 20 said side walls, a contact support member at the inside of each side wall having a terminal thereon 25 passing through a perforation in one of said end walls, a plate between the top of said contact member and said cover and a pivot pin for 30 said switch handle interposed between the top of said plate and said cover.

7. In a switch, a casing including integral bottom, side and end walls and having an open front wall, a pair of posts each spaced from and parallel to each of said side walls, a contact positioned in the space between each post and side wall, each of said side walls being provided with a slotted portion, snap switch mechanism including a pivot pin mounted in the space between 40 said posts, a removable bearing member for supporting said pin mounted in the slotted portion of the side wall and resting on one of said contacts, and a removable cover for said open front, 45 said cover being provided with a recess forming a bearing for said pivot pin.

8. In an electric toggle switch, a hollow body portion formed of insulating material and having an open side, a member for covering the open side of said body portion, said member having a central opening, a pair of stationary contacts in said body portion, one of said contacts being positioned adjacent opposite sides of the body, insulating posts between said contacts to prevent arcing therebetween, each of said stationary contacts being formed with a groove, a rib formed on opposite sides of the body portion adapted to engage the walls of the grooves of said contacts to prevent displacement of the contacts in one direction, a distance member in said body portion adjacent said stationary contact for preventing displacement of said contact in a different direction, a movable contact pivotally supported by said distance members and adapted to be moved into contact with the stationary members and an operating handle connected to said movable contact and protruding through the opening in the cover member.

CHRISTOPHER I. SMITH.
